UNITED STATES PATENT OFFICE.

WILLIAM B. GODDARD, OF BROOKLYN, NEW YORK, ASSIGNOR TO
MEURER BROS. CO., OF BROOKLYN, NEW YORK.

DESIGN FOR A TILE.

No. 37,836.

Specification for Design.

Patented Feb. 20, 1906.

Application filed August 30, 1905. Serial No. 276,460. Term of patent 14 years.

To all whom it may concern:

Be it known that I, WILLIAM B. GODDARD, a citizen of the United States, and a resident of Brooklyn, in the county of Kings and State of New York, have invented a new, original, and ornamental Design for Tiles, of which the following is a specification, reference being had to the accompanying drawings, forming part thereof.

In the accompanying drawings, forming a part of this application, Figure 1 is a perspective view of the tile constituting the subject of my invention, and Fig. 2 is an end view of the same.

As shown in the accompanying drawings, the body of the tile is of the usual form of a Spanish or ogee tile; but the end thereof is of novel configuration. Said end, as shown in

the accompanying drawings, includes a series of concentric rings or semicircular flanges or surfaces arranged in different vertical planes, so that the end has a recessed appearance. The smaller surface, or the one in reference to which the other surfaces are arranged concentric, is disposed well within the body of the tile, and the other surfaces are gradually arranged near the edge of the tile, thereby forming a series of steps angular in cross-section and semicircular in elevation.

I claim—

The ornamental design for a tile, as shown.

W. B. GODDARD.
